UNITED STATES PATENT OFFICE.

HELEN PHILLIPS LANE, OF BOSTON, MASSACHUSETTS.

DESIGN FOR A FLAG, BANNER, OR ARTICLE OF A SIMILAR NATURE.

59,015.

Specification for Design.

Patented Sept. 13, 1921.

Application filed May 16, 1918. Serial No. 235,050. Term of patent 3½ years.

To all whom it may concern:

Be it known that I, HELEN PHILLIPS LANE, a citizen of the United States, residing at Boston, in the county of Suffolk and State of Massachusetts, have invented a new, original, and ornamental Design for Flags, Banners, or Articles of a Similar Nature, of which the following is a specification, reference being had to the accompanying drawing, forming a part thereof.

The figure is an elevation of a flag showing my new design. The design is of a memorial flag and consists of a center-field of white, upon which are placed a red Latin cross and gold or yellow stars, said field being surrounded by a blue border.

I claim:—

The ornamental design for a flag, banner, or article of a similar nature as shown.

In testimony whereof I have affixed my signature.

HELEN PHILLIPS LANE.
